VALVE ASSEMBLY

Raymond A. Troy, Palisades Park, N. J., assignor
to Specialties Development Corporation, Belleville, N. J., a corporation of New Jersey

Application October 27, 1949, Serial No. 123,869

7 Claims. (Cl. 137—627.5)

1

This invention relates to improvements in valve assemblies, and is particularly directed to valve assemblies for use in connection with combined fire detecting and extinguishing systems using fire detecting means of the smoke detecting type.

Such systems are employed for the protection of spaces, compartments and the like, and usually comprise a plurality of conduits each leading from a protected space to a smoke detecting cabinet, and include means for continuously or intermittently drawing air samples from the protected spaces to the cabinet, so that when fire occurs in any of the protected spaces, the air drawn into the cabinet from that space will be laden with smoke. In such systems, the smoke detecting cabinet usually includes means for detecting the presence of smoke and identifying the space from which the smoke laden air is withdrawn.

Also, each conduit usually has a connection to a manifold or header which is in communication with a source of fire extinguishing medium, such for example as carbon dioxide under pressure. A valve assembly is generally provided in each conduit adjacent the connection to the fire extinguishing manifold, and is normally positioned to provide communication between the protected space and the smoke detecting cabinet and to close off communication with the fire extinguishing medium manifold. When fire is detected in any of the protected spaces the valve is operated to close off communication between the space and the detector cabinet and to open communication between the fire extinguishing medium manifold and the space, whereby the medium is discharged into the space to extinguish the fire.

In such systems, it is important that the line to the detector cabinet be shut off completely before the fire extinguishing valve is opened, whereby to prevent the medium from entering the cabinet.

The valve bodies of such systems are generally connected together by means of pipe connections or nipples, and, to avoid complete dismantling of such systems when it is desired to remove one of the valve bodies for repair or replacement, it has been found advantageous to employ couplings or unions between the valve bodies, whereby any desired valve body may be removed without disturbing the other valve bodies. However, while the provision of such pipe connections, nipples, couplings and/or unions has been objectionable from an economi-

2

cal viewpoint, they are still employed in such systems.

The present invention is directed to improvements in the valve assemblies of such systems, and has for one of its objects the provision of means whereby communication between a selected protected space and the smoke detecting cabinet is completely shut off before communication is effected between the fire extinguishing medium manifold and the space.

Another object resides in the provision of novel valve operating means for accomplishing the above mentioned object, such means including a resilient member for effectively closing one valve port before opening another valve port, the closing and opening of the ports being effected by a single operation.

Another object of the present invention resides in means for locking the valve in either detecting or extinguishing position, and means for indicating the position of the valve.

A further object resides in the novel construction and arrangement of the parts of the valve assembly of the present invention.

A still further object resides in novel means for interconnecting a plurality of valve assemblies to provide a manifold, without the use of pipe connections, nipples, couplings, unions or the like.

Other and further objects of the present invention will be obvious from the following detailed description and the accompanying drawings, in which drawings:

Figure 1 is a vertical sectional view of a valve assembly embodying the present invention, with certain parts shown in elevation.

Figure 2 is a plan view of the valve assembly.

Figure 3 is a front end elevational view of the assembly, and

Figure 4 is a rear end elevational view of a plurality of such valve assemblies interconnected for use in a fire detecting and extinguishing system.

Referring to the drawings in detail, the valve assembly, shown in section in Figure 1, comprises a housing 10 having a port 12 in communication with a conduit 14 leading to a protected space, compartment or the like (not shown). Another port 16, in axial alignment with the port 12, is in communication with a conduit 18 leading to a smoke detector cabinet (not shown). The port 16 has a valve seat 20 for a ball check valve member 22, which normally is held off the seat 20 by a spring 24, whereby communication normally is provided

between a protected space and smoke detector through the conduits 14 and 18.

A port 26 is provided in the housing, at right angles to the other ports, for the admission of fire extinguishing medium into a central chamber 28 which is in communication with each of the other ports. The port 26, for convenience of description, will be referred to as the gas inlet port, while the ports 16 and 12, respectively, will be referred to as the air outlet and air inlet ports. The gas inlet port 26 has a valve seat 30 for a valve member 32 having a sealing ring 34 of compressible material adapted to abut the seat 30. The valve member 32 is cup-shaped and has a shoulder 36 formed thereon against which one end of a spring 38 is seated, the other end of which is seated in a cap or plug 40. This spring normally retains the valve member 32 on its seat, whereby normally to prevent the admission of fire extinguishing medium into the central chamber 28.

A stem 42 is in axial alignment with the valve member 32 and has a guide member 44 at the inner end thereof. The guide member 44 has an enlarged portion 46 slidable within the valve member 32, which enlarged portion is recessed to accommodate a spring 48. One end of the spring 48 is seated in the recess of the guide member and its other end is seated on the inner wall of the cup-shaped valve member 32, whereby to normally bias the stem 42 to the right, as viewed in Figure 1.

The stem 42, when moved to the left, as viewed in Figure 1, will effect the unseating of the valve member 32 in the manner hereinafter described in detail. This stem also effects the operation of the ball check valve 22 through the medium of a resilient valve operating member. This operating member is in the form of a spring 50, through which the stem passes, whereby to support the same on the stem. The spring 50 has a plurality of convolutions of substantially equal diameter fitting closely on the end of the stem adjacent the guide member 44, the innermost convolutions of that portion engaging the end of the member 44. The convolutions adjacent those fitting closely on the stem gradually increase in diameter into a frusto-conical formation providing a resilient wedge comprising the resilient valve operating member. The other end of the spring is secured to a collar 52 on the stem 42, which collar is retained in position by a retaining ring 54 fitted in a groove in the stem.

The stem 42 extends out of the housing 10 through an aperture which is provided with a packing 56 seated in a recess 58 in the housing and held in position by a washer 60.

The end of the stem 42 which extends out of the housing engages a cam 62 mounted on a shaft 64 supported in lugs 66 on the housing. The cam 62 has detents at each end of its cam surface for limiting the rotation thereof, as will be described presently.

The cam has an operating lever 68 secured thereto for manual operation thereof. This lever has indicia on opposite faces thereof, one or the other of which is visible depending upon the position of the lever. The lever also has a space adjacent its extremity for receiving a "Line" number corresponding to the number of the space in communication with the air inlet port of the valve controlled by the lever.

Any desired number of the valve assemblies, shown in Figure 1, may be connected together to form a manifold, the number of assemblies em-

ployed depending upon and corresponding to, the number of spaces to be protected by the system. A manifold employing three of such assemblies is shown in Figure 4.

In order to so arrange the manifold, each of the housings or bodies 10 has a pair of apertured flanges or lugs 70 at opposite sides adapted to engage, and be bolted to, the flanges of adjacent assemblies by means of bolts 72. End plates 74 and 76 are connected to the housings at the end assemblies comprising the manifold, the end plate 74 having a connection to a conduit 75 leading to a source of supply of fire extinguishing medium, and the end plate 76 being closed by a plug 78. One side face of each housing 10 has an annular groove 80, around the gas inlet, accommodating a packing 82, which preferably is of the type known as doughnut packing. The end plate 76 has a corresponding annular groove and packing, but the end plate 74 has not. These packings serve to maintain the valve assemblies in the manifold air and gas tight.

As will be seen from Figure 2, a through gas passage 90 is provided in each body member and is in communication with the gas inlet port. As will be seen from Figure 4, when the bodies are connected to provide the manifold, the through gas passages of the bodies are in alignment, and, as will be understood from the foregoing description of the valve assembly, the fire extinguishing medium in the through gas passage normally is prevented from entering the central chamber 28 of any of the bodies until the normally closed gas inlet valve 32 of a selected body is opened.

As will be seen from the foregoing, any one of the valve bodies can readily be removed from the manifold, shown in Figure 4, by removing the bolts 72 holding that valve body in place, whereby the valve body can be slipped out of position for repair or replacement, without disturbing the other valve bodies in the system. It will also be seen that the system of the present invention does not require any pipe connections, nipples, couplings or unions between the valve bodies, as in prior structures.

The operation of the valves and the system in which these valves are employed will now be described.

Assuming that the smoke detector has indicated that fire has broken out in one of the protected spaces, the attendant will operate the lever 68 for the designated space, and upon rotating the lever in a clockwise direction, as viewed in Figure 1, the initial movement of the lever and the cam 62 connected thereto will cause the high portion 84 of the cam surface to move the stem 42 to the left, as viewed in Figure 1, whereby the wedge-shaped spring 50 will engage the ball check 22 and move it onto its seat against the action of the spring 24, thereby closing off the line to the smoke detector cabinet. Continued movement of the lever 68 and the wedge-shaped spring 50 will cause the large conical portion of the spring to collapse and ride under the ball check 22, whereby the guide member 44 will be caused to engage the bottom of the cup-shaped valve member 32 and force that valve member off its seat, thereby permitting fire extinguishing medium to enter the central chamber and pass out through the air inlet, which now becomes a gas outlet, and flow into the space in communication with the conduit 14.

When the lever 68 has been rotated to a position to effect the operation just described, a detent 86 on the cam surface will engage the end of the

stem 42 and lock the lever, the cam and the parts operated thereby in their respective operated positions.

When the lever is in the operated position the indicia thereon, namely the word "Extinguishing" will be clearly visible, whereby to indicate that the particular valve operated is in "extinguishing" position.

When the fire has been extinguished, the lever is rotated in the opposite direction until a detent 88 is engaged by the end of the stem, whereby the lever, cam and all of the operating parts are restored to their initial or "detecting" positions (Figure 1), and the indicia, namely the word "Detecting," will be visible on the lever, indicating that the assembly is in "detecting" position. By reason of the engagement of the valve stem with the detent 88 the parts will be locked in "detecting" position.

From the foregoing, it will be seen that the present invention provides a valve assembly embodying means for effectively closing one valve port during the initial operation and before opening another valve port, and wherein the operation effecting the closing and opening of the ports is effected by a single operation. It will also be seen that a plurality of the valve assemblies may be connected together into a manifold, and wherein fire extinguishing medium from a common source is prevented from being discharged except to a selected point of use.

While I have illustrated and described a preferred embodiment of my invention, it is to be understood that I do not wish to be limited to that precise form, as obviously various changes and modifications may be made therein without departing from the spirit and scope of the invention.

I claim:

1. A valve assembly of the class described comprising a body having a gas inlet port, an air inlet port, an air outlet port, and a chamber in communication with each of said ports; a normally closed gas inlet valve controlling the gas inlet port; a normally open valve controlling the air outlet port; a movable stem extending into said chamber; a substantially conical resilient member extending about said stem and connected for movement therewith upon the initial movement thereof to effect the closing of said air outlet valve; and means operable by said stem subsequent to the closing of the air outlet valve for opening the gas inlet valve, whereby gas will be permitted to enter said chamber and pass out thereof through the air inlet port.

2. A valve assembly of the class described comprising a body having a gas inlet port, an air inlet port, an air outlet port, and a chamber in communication with each of said ports; a normally closed gas inlet valve controlling the gas inlet port; a ball check member in said chamber operable to close the air outlet port; means normally biasing said check member to retain the air outlet port open; a movable stem extending into said chamber; spring means coiled about said stem and having an enlarged portion for engagement with said check member and operable by said stem to effect the closing of said air outlet port; and means operable by said stem subsequent to the closing of the air outlet port for opening the gas inlet valve, whereby gas will be permitted to enter said chamber and pass out thereof through the air inlet port.

3. A valve assembly of the class described comprising a body having a gas inlet port, an air in-

let port, an air outlet port, and a chamber in communication with each of said ports; a normally closed gas inlet valve controlling the gas inlet port; a ball check member in said chamber operable to close the air outlet port; means normally biasing said check member to retain the air outlet port open; a movable stem extending into said chamber; spring means coiled about said stem and having an enlarged portion for engagement with said check member and operable upon initial movement of said stem to effect the closing of said air outlet port, the enlarged portion of said spring means being collapsible to permit override of the stem; means operable by said stem upon further movement thereof subsequent to the closing of the air outlet port for opening the gas inlet valve, whereby gas will be permitted to enter said chamber and pass out thereof through the air inlet port; and manually operable means for moving said stem.

4. A valve assembly of the class described comprising a body having a gas inlet port, an air inlet port, an air outlet port, and a chamber in communication with each of said ports; a gas inlet valve member controlling the gas inlet port; means normally biasing the gas inlet valve member to retain the gas inlet port closed; an air outlet valve member adjacent the air outlet port controlling the flow of air therethrough; means normally biasing the air outlet valve member to retain the air outlet port open; a movable stem extending into said chamber; substantially conical resilient means extending about and operable by said stem upon the initial movement thereof and adapted to engage said air outlet valve member to effect the closing of the air outlet port, said resilient means being yieldable upon engagement with the air outlet valve to permit continued movement of the stem; and means providing a slideable connection between said stem and said gas inlet valve and including a spring operable by said stem upon further movement thereof subsequent to the closing of the air outlet valve to effect opening the gas inlet valve.

5. A valve assembly of the class described comprising a body having a gas inlet port, an air inlet port, an air outlet port, and a chamber in communication with each of said ports; a recessed gas inlet valve member controlling the gas inlet port; means normally biasing the gas inlet valve member to retain the gas inlet port closed; an air outlet valve member adjacent the air outlet port controlling the flow of air therethrough; means normally biasing the air outlet valve member to retain the air outlet port open; a movable stem extending into said chamber having means on its inner end extending into the recess of said gas inlet valve member; substantially conical resilient means extending about and operable by said stem upon the initial movement thereof and adapted to engage said air outlet valve member to effect the closing of the air outlet port, said resilient means being yieldable, upon engagement with the air outlet valve, to permit continued movement of the stem; and a spring in the recess of the gas inlet valve member and operable by said stem means upon further movement thereof subsequent to the closing of the air outlet valve to effect opening the gas inlet valve.

6. A valve assembly of the class described comprising a body having a gas inlet port, an air inlet port, an air outlet port, and a chamber in communication with each of said ports; a valve member normally closing said gas inlet port; a normally open valve for said air outlet port in-

cluding a valve member structurally independent of said gas inlet port valve member; a movable stem extending into said chamber having its inner end adjacent and relatively movable with respect to said gas inlet valve member; means including a spring providing a slidable connection between said gas inlet valve member and the inner end of said stem arranged to enable said stem to effect unseating of said gas inlet valve member; and means extending about said stem and movable therewith and operable by said stem upon initial movement thereof to effect closing of said air outlet valve member.

7. A valve assembly of the class described comprising a body having a gas inlet port, an air inlet port, an air outlet port, and a chamber in communication with each of said ports; a valve member for said gas inlet port formed with a bore facing said chamber; a spring normally causing said valve member to close said gas inlet port; a spring in said bore; a valve member for said air outlet port; a spring normally urging said last mentioned valve member to maintain said air outlet port open; a stem slidably mounted on said body and extending into said chamber ad-

15 jacent and relatively movable with respect to said air outlet valve member and having means on its inner end positioned in said bore of said gas inlet valve member for movement therein and engaging 5 the spring therein; means extending about said stem normally out of contact with said air outlet valve member adapted to engage said air outlet valve member to effect closing thereof; and means for moving said stem inwardly with respect to 10 said bore to cause said means extending about said stem to engage and close said air outlet valve member upon initial movement of said stem and to thereafter cause said stem to unseat said gas inlet valve member and open said gas inlet port.
